[57] CLAIM

The ornamental design for a portion of a shoe sole, as shown and described.

DESCRIPTION

FIG. 1 is a side elevational view of a portion of a shoe sole showing my new design;

FIG. 2 is a frontal perspective view thereof;

FIG. 3 is a rear perspective view thereof; and,

FIG. 4 is a top plan view thereof.

The uneven broken line showing of the remainder of the shoe sole is for illustrative purposes only and forms no part of the claimed design.
